UNITED STATES PATENT OFFICE

99,686

DESIGN FOR A WEDDING RING

Guy A. Tomlinson, Detroit, Mich., assignor
to Traub Manufacturing Company, Detroit,
Mich.

Application February 24, 1936, Serial No. 61,301

Term of patent 14 years

To all whom it may concern:

Be it known that I, Guy A. Tomlinson, a citizen of the United States, residing at Detroit, in the county of Wayne and State of Michigan, have invented a new, original, and ornamental Design for Wedding Rings, of which the following is a specification, reference being had to the accompanying drawing, forming a part thereof.

Fig. 1 is a perspective view of a ring embodying my invention;

Fig. 2 is a fragmentary plan view thereof showing more clearly the details of the ring.

Fig. 3 is a cross-sectional view taken on line 3—3 of Fig. 1.

I claim:

The ornamental design for a wedding ring, as shown.

GUY A. TOMLINSON.
